DESIGN FOR A DRESS

Tora Coleman, New York, N. Y.

Application November 27, 1936, Serial No. 66,159

Term of patent 3½ years

To all whom it may concern:

Be it known that I, Tora Coleman, a citizen of the Republic of Latvia, residing at No. 301 East 38th Street, city of New York, Borough of Manhattan, county of New York, and State of New York, have invented a new, original, and ornamental Design for a Dress, of which the following is a specification, reference being had to the accompanying drawing, forming a part thereof.

Figure 1 is a front view of a dress embodying my design.

Figure 2 is a back view thereof.

The characteristic feature of the design consists of a panel extending along the entire front

and back of the dress, narrowed at the waist and buttoned at the front along the center which is scalloped, the side edges of said panel being stitched to the dress and at the front partially provided with scallops unattached from the underlying fabric as shown, the ornamental appearance being completed by the scalloped, gathered sleeves, scalloped round neck and belt at the waist.

I claim:

The ornamental design for a dress as shown and described.

TORA COLEMAN.
